**CROSS-REFERENCE TO RELATED
APPLICATIONS**

This U.S. non-provisional patent application claims priority under 35 U.S.C. § 119 of Korean Patent Application Nos. 10-2022-0037167, filed on Mar. 25, 2022, 10-2022-0109856, filed on Aug. 31, 2022, and 10-2022-0133276, filed on Oct. 17, 2022, the entire contents of each of which are incorporated herein by reference.

BACKGROUND

The present disclosure herein relates to a composition for depositing a silicon-containing layer and a method of depositing a silicon-containing layer using the same.

As semiconductor devices are highly integrated, circuits constituting the semiconductor device are miniaturized. Accordingly, the size of electronic components (such as transistors or capacitors) is reduced, and the thickness of gate insulating layers and/or the dielectric layers of capacitors is also reduced. Accordingly, leakage current properties may have a greater effect on electronic devices including said layers. As such, minimizing leakage current in such layers is required in match the industry demands. In order to achieve such requirements, various studies are conducted. In addition, when forming gate insulating layers or the dielectric layers of capacitors, it is also beneficial to achieve excellent step coverage properties and reduce cell distribution.

SUMMARY

The task for solving of the present disclosure is to provide a method of depositing a silicon-containing layer, by which a silicon-containing layer of high quality may be formed.

Another task for solving of the present disclosure is to provide a composition for depositing a silicon-containing layer, by which a silicon-containing layer of high quality may be formed.

To achieve the task, embodiments of the inventive concepts provide a method of depositing a silicon-containing layer, including feeding a silicon precursor into a process chamber in which a substrate is loaded such that the silicon precursor is adsorbed onto the substrate, the silicon precursor represented by Formula 1.

In Formula 1, A^1 is a heterocyclic group and includes one or more nitrogen, R^1 is hydrogen or an alkyl group of 1~6 carbon atoms, and R^2 and R^3 are each independently an alkyl group of 1~6 carbon atoms.

In order to achieve the other task, embodiments of the inventive concepts provide the silicon precursor of Formula 1.

2

BRIEF DESCRIPTION OF THE FIGURES

The accompanying drawings are included to provide a further understanding of the inventive concept, and are incorporated in and constitute a part of this specification. The drawings illustrate example embodiments of the inventive concept and, together with the description, serve to explain principles of the inventive concept. In the drawings:

FIGS. 1A-1D are a process diagram showing a method of depositing a silicon-containing layer according to some example embodiments of the inventive concepts;

FIG. 2 is a thermogravimetric (TG) graph of silicon precursors prepared in Examples 1 to 3;

FIG. 3 is a differential scanning calorimetry (DSC) graph of silicon precursors prepared in Examples 1 to 3;

FIG. 4 is a vaporization pressure graph of silicon precursors prepared in Examples 1 to 3;

FIG. 5 is a Fourier-transform infrared spectroscopy (FT-IR) graph of a layer formed in Example 4 using a silicon precursor of Example 1; and

FIG. 6 is a FT-IR graph of a layer formed in Example 5 using a silicon precursor of Example 2.

DETAILED DESCRIPTION

Some example embodiments of the inventive concepts will be explained in more detail with reference to the accompanying drawings. It will be understood that words or terms used in the specification and claims shall not be interpreted as the meaning defined in commonly used dictionaries, but that such words or terms should be interpreted as having a meaning that is consistent with their meaning in the context of the relevant art and the technical idea of the invention, based on the principle that an inventor may properly define the meaning of the words or terms to best explain the invention.

Accordingly, the configurations shown in embodiments in the specification are only some example embodiments of the inventive concepts and do not represent all of the technical scope of the inventive concepts. Therefore, it should be understood that various equivalents and modifications, which are replaceable with the embodiments are also possible.

The silicon precursor according to the inventive concept has a structure of Formula 1 and includes a heterocyclic group (A^1). The composition for depositing a silicon-containing layer according to the inventive concept includes a silicon precursor of Formula 1 (described in further detail below).

The heterocyclic group according to at least one embodiment of the inventive concept may include one or more nitrogen atoms and 2 to 12 carbon atoms. Further, the heterocyclic group may further include 1 to 4 heteroatoms, selected from oxygen, sulfur, or the like, in addition to the one or more nitrogen atoms. The heterocyclic group may include, for example, heteroaryl, heterocycloalkyl, heterocycloalkenyl, and/or the like, preferably, heterocycloalkyl. Preferably, the heterocyclic group may include 3-atom to 8-atom, preferably, a 3-atom to 6-atom heterocycloalkyl, containing one or more nitrogen, particularly, azetidinyl, morpholinyl, piperazinyl, and/or the like.

Alkyl according to an embodiment of the inventive concept is a saturated linear or branched hydrocarbon chain radical composed of only carbon and hydrogen.

FIGS. 1A-1D are a process diagram showing a method of depositing a silicon-containing layer according to at least some example embodiments of the inventive concepts.

The method of depositing a silicon-containing layer includes performing a deposition process cycle shown in FIGS. 1A-D several times. The deposition method is preferably an atomic layer deposition (ALD). One deposition process cycle includes a step of feeding a silicon precursor 3, represented by Formula 1 and having the heterocyclic group, or a composition including the silicon precursor 3 into a process chamber in which a substrate 1 is loaded so as to adsorb the silicon precursor 3 on the substrate (first step, FIG. 1A).

<Formula 1>

In Formula 1, A^1 is the heterocyclic group including one or more nitrogen; R^1 is hydrogen or an alkyl group of 1~6 carbon atoms; and R^2 and R^3 are each independently an alkyl group of 1~6 carbon atoms.

In at least some embodiments, the heterocyclic group may have a ring type formed by 2 to 8 carbon atoms and one or more heteroatoms selected from the atoms of nitrogen (N), sulfur (S) and oxygen (O). R^1 may be hydrogen or an alkyl group of 1~4 carbon atoms. R^2 may be an alkyl group of 1~4 carbon atoms. R^3 may be an alkyl group of 1~4 carbon atoms.

The silicon precursor of Formula 1 may be referred to as a heterocyclic dialkoxy alkyl silane and/or a heterocyclic dialkoxy silane.

In the first step, a composition including the silicon precursor 3 may be fed.

In at least some embodiments, A^1 may be represented by Formula 2 or Formula 3.

<Formula 2>

<Formula 3>

In Formula 2, n may be an integer of 0 to 5, and in Formula 3, p and q may be each independently an integer of 0 to 2. A^2 may be an oxygen atom (O) or NR^4 , where R^4 may be an alkyl group of 1~6 carbon atoms.

In these examples, the silicon precursor 3 may have a structure of Formula 1-1 or 1-2.

<Formula 1-1>

-continued

<Formula 1-2>

In Formula 1-1 or Formula 1-2, n may be an integer of 0 to 5, p and q may be each independently an integer of 0 to 2, and A^2 may be an oxygen atom (O) or NR^4 , where R^4 may be an alkyl group of 1~6 carbon atoms.

In at least some embodiments, in Formula 1-1 and Formula 1-2, A^2 may be included in a heterocyclic group including one or more nitrogen and having 2 to 6 carbon atoms, R^1 may be hydrogen or an alkyl group of 1~4 carbon atoms, and R^2 and R^3 may be each independently an alkyl group of 1~4 carbon atoms.

In at least some embodiments, the silicon precursor 3 may have at least one structure among Formulae 2-1 to 2-7.

1 (second step), feeding a reaction gas into the process chamber for the reaction with the adsorbed/bonded silicon precursor **3** on the substrate **1** (third step, FIG. 1C), and purging unreacted reaction gas with the silicon precursor **3**.

5 The reaction gas may be an oxidizer, and may include, for example, at least one of oxygen (O₂), ozone (O₃), oxygen plasma, hydrogen, hydrogen plasma, ammonia, and/or nitrogen plasma. The resulting silicon-containing layer may be a silicon oxide layer, a silicon nitride layer, or a silicon oxynitride layer. Oxygen (O₂) is fed as the reaction gas in the illustration of FIG. 1A, as an illustrative example, but, as noted above, the example embodiments are not limited thereto. The reaction gas may be fed in a flow rate of about 1000-4000 sccm.

10 The reaction gas may react with carbon atoms included in the R¹, the OR² and the A¹ of the silicon precursor **3** to produce gases having small molecular weights (such as CO₂, CO, and CH₄). Accordingly, as illustrated in FIG. 1D, the R¹, OR², R³ and A¹ of the silicon precursor **3** may be 15 removed to form a silicon oxide layer **5** having a thickness of one atomic layer.

20 By repeating the deposition process cycle several times, the silicon oxide layer **5** in FIG. 1D may be stacked upward to a desired thickness.

25 In at least one embodiment, the silicon precursor **3** may be provided in a vapor state. For example, the silicon precursor **3** may be heated to a temperature wherein the silicon precursor **3** does not degrade, for example, to about 30-120° C., but the example embodiments are not limited thereto. In 30 at least some embodiments, when feeding the silicon precursor **3** of the first step, a carrier gas may also be supplied. For example, the carrier gas may be an inert gas such as a nitrogen (N₂) gas. The carrier gas may be fed in a flow rate of, for example, about 50-200 sccm (standard cubic centimeters per minute). In at least some examples, the first step 35 may be performed for about 5-20 seconds per deposition. The third step may be performed for about 10-20 seconds per oxidation.

40 The purging process of the second step and the fourth step may be performed by feeding, for example, an inert gas such as nitrogen gas. In this case, the nitrogen gas may be fed in a flow rate of about 1000-3000 sccm. The second step may be performed for a longer time than the fourth step. For example, the second step may be performed for about 20-40 seconds and the fourth step may be performed for about 1-10 seconds. Accordingly, the process defects due to unreacted silicon precursor may be prevented.

45 The method for depositing a silicon-containing layer according to the inventive concepts uses the silicon precursor represented by Formula 1, and a dense silicon-containing layer (for example, a silicon oxide layer) may be formed without halogen atoms. Accordingly, an electronic device including the silicon-containing layer formed according to the inventive concepts may prevent/reduce leakage current.

50 55 The silicon-containing layer may be used as a gate insulating layer, the dielectric layer of a capacitor, the tunnel insulating layer of a nonvolatile memory device, and/or the like.

Hereinafter, preferred embodiments (experimental embodiments) according to the inventive concepts will be 60 explained.

[Example 1] Synthesis of
Morpholinodimethoxymethylsilane

65 Under an anhydrous and inert atmosphere, morpholine (HN(CH₂)₂(CH₂)₂O, 294.13 g, 3.38 mol) and tetrahydrofuran (C₄H₈O, 1,746 g, 20.26 mol) were injected to a

Referring to FIG. 1A, in Formula 1, the heterocyclic group of A¹ has high affinity with "H" of the OH group of the surface of the substrate **1**, and through this affinity, the silicon precursor **3** is adsorbed on the surface of the substrate **1** well. Accordingly, the heterocyclic group of A¹ may function as an adsorption functional group for an atomic layer deposition (ALD) process.

The silicon precursor **3** including one heterocyclic group of A¹ does not deteriorate vaporization and at the same time, shows excellent thermal stability and reactivity, and thus is suitable for an ALD process.

In Formula 1, the alkyl group of R¹ is hydrogen or an alkyl group of 1~6 carbon atoms, particularly, hydrogen or an alkyl group of 1~4 carbon atoms, more particularly, hydrogen or a methyl group or an ethyl group (having 1 or 2 carbon atoms). Accordingly, the alkyl group of R¹ has a relatively small molecular weight. Accordingly, the molecular weight of the silicon precursor may be reduced to increase vaporization. The alkyl group of R¹ may act as a functional group improving vaporization.

In Formula 1, the alkoxy groups of —OR² and/or —OR³ have high bonding force with Si. Accordingly, if the silicon precursor includes the alkoxy groups of —OR² and/or —OR³, the decomposition of the silicon precursor may not be easy, and the silicon precursor may be applied to a high temperature (for example, about 550° C.-700° C.) suitable for an ALD process (e.g., corresponding to an ALD window section).

More specifically, the silicon precursor of the inventive concepts does not include a halogen atom such as chlorine. If the silicon precursor includes a halogen atom, the halogen atom has high bonding force with the silicon, and during the depositing of a silicon-containing layer, the probability of the presence of the halogen atom in the silicon-containing layer increases. In these cases, the halogen atom may act as a trap site for charges, and thus if the silicon-containing layer includes the halogen atom like this, problems that may related to the trap site of charge and/or the increased leakage current may occur. However, the silicon precursor of the inventive concepts does not include a halogen atom, and therefore such problems may be reduced and/or prevented.

During the feeding of the silicon precursor **3** to adsorb the silicon precursor **3** on the substrate (first step, FIG. 1A), the temperature of the substrate **1** may preferably be maintained at about 550° C.-700° C., more preferably, about 550° C.-650° C. At this temperature, R¹ or R³ of the silicon precursor **3** and the hydrogen ("H") of the surface of the substrate **1** may be separated, and a portion of the silicon precursor **3** may be bonded to the oxygen ("O") at the surface of the substrate **1** as illustrated in FIG. 1B.

The one deposition process cycle may further include purging the silicon precursor **3** not adsorbed on the substrate

flame-dried 5000 mL flask. Then, 2.68 M n-butyllithium (C_4H_9Li , 1,261.9 mL, 3.38 mol) was slowly injected while maintaining the temperature at about $-20^\circ C$. The resultant was stirred at room temperature for about 5 hours to prepare a morpholine lithium salt ($C_4H_8LiN(CH_2)_2(CH_2)_2O$). To a mixture solution of hexane (C_6H_{14} , 1000 mL) and trimethoxymethylsilane ($((CH_3O)_3SiCH_3$), 460 g, 3.38 mol), the thus prepared morpholine lithium salt ($C_4H_8LiN(CH_2)_2(CH_2)_2O$) was slowly added while maintaining at about $-20^\circ C$.

After finishing the addition, the temperature of the reaction solution was slowly raised to room temperature, and stirring was performed at room temperature for about 6 hours. After finishing the reaction, the reaction mixture was filtered to remove lithium methoxide ($LiOCH_3$), and a solvent of a filtrate was removed under a reduced pressure and distilled at a temperature of about $32^\circ C$. and a reduced pressure of about 0.362 torr to obtain morpholinodimethoxymethylsilane ($((CH_3O)_2SiCH_3N(CH_2)_2(CH_2)_2O$, 397 g, 2.07 mol) of Formula 2-8 (yield 67.3%).

The composition of the morpholinodimethoxymethylsilane was confirmed using nuclear magnetic resonance (^1H -NMR (C_6D_6): δ 3.39 (s, 6H(CH_3O)₂Si), 2.80 (t, 4H, ($SiN(CH_2)_2$), 3.42 (t, 4H($SiN(CH_2)_2(CH_2)_2O$), 0.01 (s, 3H $SiCH_3$) and ^{29}Si -NMR (C_6D_6): δ -31.7 ($((CH_3O)_2SiCH_3N(CH_2)_2(CH_2)_2O$)).

[Example 2] Synthesis of
Pyrrolidinodimethoxymethylsilane

Under an anhydrous and inert atmosphere, pyrrolidine ($HN(CH_2)_4$, 249.82 g, 3.51 mol) and hexane (C_6H_{14} , 1,720 g, 19.9 mol) were injected to a flame-dried 4000 mL flask. Then, 2.50 M n-butyllithium (C_4H_9Li , 1,405.9 mL, 3.51 mol), was slowly injected while maintaining the inner temperature to about $-20^\circ C$., and the resultant was stirred at room temperature for about 5 hours to prepare a pyrrolidine lithium salt ($C_4H_8LiN(CH_2)_4$). To a mixture solution of hexane (C_6H_{14} , 1000 mL) and trimethoxymethylsilane ($((CH_3O)_3SiCH_3$), 478.5 g, 3.51 mol), the thus prepared pyrrolidine lithium salt ($C_4H_8LiN(CH_2)_4$) was slowly added while maintaining the temperature at about $-20^\circ C$.

After finishing the addition, the temperature of the reaction solution was slowly raised to room temperature, and stirring was performed at room temperature for about 6 hours. After finishing the reaction, the reaction mixture was filtered to remove lithium methoxide ($LiOCH_3$), and the solvent of the filtrate was removed under a reduced pressure and distilled at a temperature of about $29^\circ C$. and a reduced pressure of about 1 torr to obtain pyrrolidinodimethoxymethylsilane ($((CH_2)_2(CH_2)_2NSiCH_3(OCH_3)_2$, 468.1 g, 2.67 mol) of Formula 2-4 (yield 76%).

The composition of the pyrrolidinodimethylmethoxysilane was confirmed using nuclear magnetic resonance (^1H -NMR (C_6D_6): δ 3.37 (s, 6H(CH_3O)₂Si), 2.96 (m, 4H, ($CH_2)_2(CH_2)_2NSi$), 1.52 (m, 4H($CH_2)_2(CH_2)_2NSi$), 0.03 (s, 3H $SiCH_3$) and ^{29}Si -NMR (C_6D_6): δ -30.6 ($((CH_2)_2(CH_2)_2NSiCH_3(OCH_3)_2$)).

[Example 3] Synthesis of
Morpholinodimethoxysilane

Under an anhydrous and inert atmosphere, trimethoxysilane ($Si(CH_3O)_3H$, 400 g, 3.27 mol), aluminum chloride ($AlCl_3$, 0.65 g, 0.005 mol) and acetyl chloride (CH_3COCl , 334 g, 4.25 mol) were injected to a flame-dried 2000 mL flask at room temperature, and stirred while maintaining the

temperature to about $50^\circ C$. for about 8 hours to prepare dimethoxymethylsilane ($SiH(CH_3O)_2Cl$). The thus prepared dimethoxymethylsilane ($SiH(CH_3O)_2Cl$) was filtered and purified to obtain 213 g (1.68 mol).

Under an anhydrous and inert atmosphere morpholine ($HN(CH_2)_2(CH_2)_2O$, 133.9 g, 1.68 mol) was slowly added to a flame-dried 4000 mL flask containing a mixture solution of dimethoxymethylsilane ($SiH(CH_3O)_2Cl$, 213 g, 1.68 mol) and triethylamine ($NH(CH_2CH_3)_3$) in hexane (C_6H_{14} , 2200 mL), while being maintaining at room temperature. After finishing the addition, the mixture was stirred at room temperature for about 6 hours. After finishing the reaction, the reaction mixture was filtered to remove triethylamine hydrochloride ($NH(CH_2CH_3)_3HCl$), and the solvent of a filtrate was removed under a reduced pressure and distilled at a temperature of about $22^\circ C$. and a reduced pressure of about 0.769 torr to obtain morpholinodimethoxysilane ($((CH_3O)_2SiHN(CH_2)_2(CH_2)_2O$, 152 g, 0.857 mol) of Formula 2-7 (yield 50.4%).

The composition of the morpholinodimethoxysilane was confirmed using nuclear magnetic resonance (^1H -NMR (C_6D_6): δ 3.32 (s, 6H(CH_3O)₂Si), 2.79 (t, 4H, ($SiN(CH_2)_2$), 3.36 (t, 4H($SiN(CH_2)_2(CH_2)_2O$), 4.48 (s, 1H SiH)).

FIG. 2 is a thermogravimetric (TG) graph of silicon precursors prepared in Examples 1 to 3.

Referring to FIG. 2, it could be found that the masses of morpholinodimethoxymethylsilane, pyrrolidinodimethoxymethylsilane and morpholinodimethoxysilane, which are the silicon precursors prepared in Examples 1 to 3, were stably maintained at almost 100%, while the temperature was maintained at under about $200^\circ C$., but were less than about 1% at a temperature higher about $200^\circ C$., and residual masses were rarely confirmed. From this, it could be found that each of morpholinodimethoxymethylsilane, pyrrolidinodimethoxymethylsilane and morpholinodimethoxysilane was vaporized at a temperature around $200^\circ C$. Accordingly, it could be found that intermolecular decomposition/reaction did not occur in the morpholinodimethoxymethylsilane, pyrrolidinodimethoxymethylsilane and morpholinodimethoxysilane, and material storage stability was excellent.

FIG. 3 is a differential scanning calorimetry (DSC) graph of silicon precursors prepared in Examples 1 to 3.

Referring to FIG. 3, most of the morpholinodimethoxymethylsilane, pyrrolidinodimethoxymethylsilane and morpholinodimethoxysilane, which are the silicon precursors prepared in Examples 1 to 3, showed not much change in heat at a temperature of less than about $500^\circ C$. at an atmospheric pressure. Accordingly, it could be found that the thermal decomposition did not arise for the morpholinodimethoxymethylsilane, pyrrolidinodimethoxymethylsilane and morpholinodimethoxysilane, and that the morpholinodimethoxymethylsilane, pyrrolidinodimethoxymethylsilane and morpholinodimethoxysilane are thermally stable at a temperature of up to (at least) about $500^\circ C$. at an atmospheric pressure. Since an ALD process is performed at a low pressure, the morpholinodimethoxymethylsilane, pyrrolidinodimethoxymethylsilane and morpholinodimethoxysilane may be stable at a temperature of about $550^\circ C$.- $700^\circ C$. That is, it could be found that the morpholinodimethoxymethylsilane, pyrrolidinodimethoxymethylsilane and morpholinodimethoxysilane prepared are suitable for an ALD process.

FIG. 4 is a vaporization pressure graph of silicon precursors prepared in Examples 1 to 3.

Referring to FIG. 4, it could be found that the vapor pressure of the morpholinodimethoxymethylsilane, pyrrolidinodimethoxymethylsilane and morpholinodimethoxysilane

lane, which are the silicon precursors prepared in Examples 1 to 3, increased in accordance with the temperature. By using this, the morpholinodimethoxymethylsilane, pyrrolidinodimethoxymethylsilane and morpholinodimethoxysilane could be vaporized and fed in an ALD process. Therefore, it could be found that the morpholinodimethoxymethylsilane, pyrrolidinodimethoxymethylsilane and morpholinodimethoxysilane are suitable for an ALD process.

From FIG. 2 to FIG. 4, it could be found that the morpholinodimethoxymethylsilane, pyrrolidinodimethoxymethylsilane and morpholinodimethoxysilane have excellent thermal stability and a vapor pressure suitable for ALD.

[Example 4] Deposition of Silicon Oxide Layer by
Atomic Layer Deposition (ALD) Using the
Morpholinodimethoxymethylsilane of Example 1

On silicon substrates (corresponding to reference numeral 1 in (a) of FIG. 1), which are bare wafers, an ALD deposition process was performed to deposit silicon oxide layers. In this case, the compound of Example 1, morpholinodimethoxymethylsilane was used as the silicon precursor 3, and a 200-300 mm Batch Type ALD equipment of a vertical furnace type was used. According to the change of the conditions of the ALD deposition process, for example, the temperature of the silicon substrate, the feeding time of the silicon precursor (will be referred to as a source below) and the feeding time of a reaction gas (will be referred to as a reactant below), the growth rate, the composition and the etching rate of the deposited silicon oxide layer were observed. The temperature of the silicon substrate was changed in a range of about 550-650°C. (corresponding to the "evaluation of ALD window"). The feeding time of the silicon precursor was changed in about 5-20 seconds (corresponding to the "evaluation on source feeding time split"). The feeding time of the reaction gas was changed in about 10-20 seconds (corresponding to the "evaluation on reactant feeding time").

The ALD deposition process was performed by repeating the process cycle several times. One process cycle included the processes below.

A stainless-steel bubbler container was charged with morpholinodimethoxymethylsilane, and was maintained at about 70°C.

First, the morpholinodimethoxymethylsilane in the stainless steel bubbler container was vaporized and fed/transported to the silicon substrate 1 in a process chamber with about 100 sccm of a nitrogen gas as a carrier gas and adsorbed on the silicon substrate 1. Second, about 2,000 sccm of a nitrogen gas was fed for about 30 seconds as a purge gas to purge/remove the silicon precursor not adsorbed. Third, oxygen and hydrogen were fed as reactants. In this case, oxygen was fed in a flow rate of about 3,500 sccm, and hydrogen was fed in a flow rate of about 1,200 sccm. Fourth, a nitrogen gas was fed in a flow rate of about 2,000 sccm for about 5 seconds as a purge gas to purge/remove by-products and remaining reactants.

Hereinafter, the particular conditions of the deposition process of the silicon oxide layer are shown in Table 1.

TABLE 1

5	Silicon oxide layer deposition conditions	Source	
		Morpholinodimethoxymethylsilane	Reactant feeding time split
10	Substrate temperature (° C.)	600	600
	Silicon precursor Heating temperature (° C.)	70	70
	Purge gas Feeding time (sec)	5-20	10
	Flow rate (sccm)	2000	2000
	Time (sec)	30	30
	Reactant Oxygen flow rate (sccm)	3000	3500
	Hydrogen flow rate (sccm)	1200	1200
15	Time (sec)	10	10-20
	Purge Flow rate (sccm)	2000	2000
	Time (sec)	5	5
	Deposition process cycle number	100	140

20 The thickness of the silicon oxide layer deposited under the conditions of Table 1 was measured through ellipsometer, and the growth rate and refractivity of the deposited silicon oxide layer are shown in Table 2.

TABLE 2

Evaluation	Substrate temperature (° C.)	Precursor Feeding time (sec)	Layer thickness [Å]	Growth rate [Å/cycle]	Refractivity
30	Source feeding time split	600	5	0.86	1.48
		10	92	0.92	1.48
		20	105	1.05	1.48
35	Reactant feeding time split	600	10	0.93	1.48
		20	133	0.95	1.48

40 According to Table 2, the refractivity of the deposited silicon oxide layer was maintained to about 1.48. It is considered because the thickness of the deposited silicon oxide layer is thin to a degree of about 100 Å.

45 In Table 3 below, particular deposition conditions of a silicon oxide layer on ALD window evaluation are shown, and in this case, the evaluation was conducted while fixing a source feeding time (feeding time of silicon precursor) to 10 seconds.

TABLE 3

50	Silicon oxide layer deposition conditions	Source	
		Morpholinodimethoxymethylsilane	ALD window
55	Substrate temperature (° C.)	550-650	
	Silicon precursor Heating temperature (° C.)	70	
	Purge gas Feeding time (sec)	10	
	Flow rate (sccm)	2000	
	Time (sec)	30	
	Reactant Oxygen flow rate (sccm)	3500	
	Hydrogen flow rate (sccm)	1200	
	Time (sec)	10	
60	Purge Flow rate (sccm)	2000	
	Time (sec)	5	
	Deposition process cycle number	140	

65 The thickness of the silicon oxide layer deposited under the conditions of Table 3 was measured through ellipsometer, and the growth rate and refractivity of the deposited silicon oxide layer are shown in Table 4.

11

TABLE 4

Evaluation	Reactant	Substrate temperature (° C.)	Layer thickness [Å]	Growth rate [Å/cycle]	Refractivity
ALD window	Oxygen and hydrogen	550	128	0.91	1.48
		600	130	0.93	1.48
		650	145	1.04	1.48

According to Table 4, the refractivity of the deposited silicon oxide layer was maintained to about 1.48. It is considered because the thickness of the deposited silicon oxide layer is thin to a degree of about 100 Å.

The composition and ratio of the silicon oxide layer deposited under ALD window (about 550-650° C.) conditions were analyzed using an X-ray photoelectron spectroscopy (XPS) and a Secondary Ion Mass Spectrometry (SIMS), and the results are shown in Table 5.

TABLE 5

Substrate temperature (° C.)	Composition of layer (at %)				Si/O _x ratio
	C	N	Si	O	
550	0	0	34.3	65.7	0.52
600	0	0	34.4	65.6	0.52
650	0	0	34.2	65.8	0.52

Referring to Table 5, it was confirmed that no carbon and nitrogen were found in the silicon oxide layer formed in Example 4. This may mean that charge trap due to carbon or nitrogen atoms in the silicon oxide layer was also not produced. Therefore, leakage current through the silicon oxide layer could be prevented/reduced. In addition, the ratio of silicon/oxygen in the silicon oxide layer was maintained to similar values, even though the temperature of the silicon substrate increased. In addition, the wet etching rate of the deposited silicon oxide layer in a range of about 550 to about 650° C. was analyzed. Wet etching was performed twice for about 10 seconds each using hydrofluoric acid (H₂O:HF=200:1) as an etchant, and the thickness was measured by the number of etchings. The results are shown in Table 6.

TABLE 6

Substrate temperature (° C.)	Wet etching rate (Å/sec)	
	1 st etching	2 nd etching
550	5.6	3.2
600	4.2	3.3
650	2.9	2.7

According to Table 6, it could be found that the etching rate during the second etching by which accurate etching rate could be found, was a value of less than about 3.5 Å/sec, and very excellent etching resistance was confirmed. In addition, according to the increase of the temperature of the substrate from about 550° C. to about 650° C., the etching rate of the deposited silicon oxide layer was reduced. Accordingly, it could be found that the etching resistance of the deposited silicon oxide layer became excellent with the increase of the temperature of the substrate during the deposition.

The reduction of the etching rate of the layer may mean the increase of the density of the layer. For example, the silicon oxide layer deposited under the above-described

12

deposition conditions using the silicon precursor according to the inventive concept has high density, and does not result in leakage current. In addition, the silicon precursor according to the inventive concept does not include a halogen atom, and there is no concern of remaining a halogen element in the deposited silicon oxide layer. Accordingly, the formation of trap by a halogen element is prevented, and leakage current is not produced further.

10 [Example 5] Deposition of Silicon Oxide Layer by Atomic Layer Deposition (ALD) Using the Pyrrolidinodimethoxymethylsilane of Example 2

15 On silicon substrates (corresponding to reference numeral 1 in (a) of FIG. 1), which are bare wafers, an ALD deposition process was performed to deposit silicon oxide layers. In this case, the compound of Example 2, pyrrolidinodimethoxymethylsilane was used as the silicon precursor 3, and a 200-300 mm Batch Type ALD equipment of a vertical 20 furnace type was used. According to the change of the conditions of the ALD deposition process, for example, the temperature of the silicon substrate, the feeding time of the silicon precursor (will be referred to as a source below), and the feeding time of a reaction gas (will be referred to as a 25 reactant below), the growth rate, the composition and the etching rate of the deposited silicon oxide layer were observed. The temperature of the silicon substrate was maintained in a range of about 550-700° C. (corresponding to the “evaluation of ALD window”). The feeding time of the silicon precursor 3 was about 2-20 seconds (corresponding to the “evaluation on source feeding time split”). The feeding time of the reaction gas was about 2-20 seconds (corresponding to the “evaluation on reactant feeding time”).

30 The ALD deposition process was performed by repeating the process cycle several times. One process cycle included the processes below.

A stainless-steel bubbler container was charged with the silicon precursor of pyrrolidinodimethoxymethylsilane, and 40 was maintained at about 48° C.

45 First, pyrrolidinodimethoxymethylsilane in the stainless steel bubbler container was vaporized and fed/transported to a silicon substrate 1 in a process chamber with about 100 sccm of a nitrogen gas as a carrier gas and adsorbed on the silicon substrate 1. Second, about 2,000 sccm of a nitrogen gas was fed as a purge gas for about 30 seconds to purge/remove the silicon precursor not adsorbed. Third, oxygen and hydrogen were fed as reactants. In this case, oxygen was fed in a flow rate of about 3,500 sccm, and hydrogen was fed 50 in a flow rate of about 1,200 sccm. Fourth, a nitrogen gas was fed in a flow rate of about 2,000 sccm as a purge gas for about 5 seconds to purge/remove by-products and remaining reactants.

55 Hereinafter, the particular conditions of the deposition process of a silicon oxide layer are shown in Table 7.

TABLE 7

Silicon oxide layer deposition conditions	Source	
	Pyrrolidinodimethoxymethylsilane	
Substrate temperature (° C.)	600	600
Heating temperature (° C.)	48	48
precursor Feeding time (sec)	2-20	10
Purge gas Flow rate (sccm)	2000	2000

TABLE 7-continued

		Source		5
		Pyrrolidinodimethoxymethylsilane		
Silicon oxide layer deposition conditions		Source feeding time split	Reactant feeding time split	
Reactant	Time (sec)	30	30	10
Oxygen flow rate (sccm)	3000	3500		
Hydrogen flow rate (sccm)	1200	1200		
Purge	Time (sec)	10	10-20	15
Flow rate (sccm)	2000	2000		
Deposition process cycle number	5	5		
	100	140		

The thickness of the silicon oxide layer deposited under the conditions of Table 7 was measured through ellipsometer, and the growth rate and refractivity of the deposited silicon oxide layer are shown in Table 8.

TABLE 8

Evaluation	Substrate temperature (° C.)	Precursor Feeding time (sec)	Layer thickness [Å]	Growth rate [Å/cycle]	refractivity	
Source feeding time split	600	2	83	0.83	1.48	20
		5	96	0.96	1.48	
		10	101	1.01	1.48	
		20	107	1.07	1.48	
Reactant feeding time split	600	10	139	0.99	1.48	25
		20	145	1.03	1.48	

According to Table 8, the refractivity of the deposited silicon oxide layer was maintained to about 1.48. It is considered because the thickness of the deposited silicon oxide layer is thin to a degree of about 100 Å.

In Table 9 below, a particular deposition method of a silicon oxide layer on ALD window evaluation is shown, and in this case, the evaluation was conducted while fixing a source feeding time (feeding time of silicon precursor) to 5 seconds and 10 seconds.

TABLE 9

Silicon oxide layer deposition conditions		Source	50
		Pyrrolidinodimethoxymethylsilane	
		ALD window	
Substrate temperature (° C.)	550-700		
Silicon precursor	Heating temperature (° C.)	48	
Feeding time (sec)	5-10		55
Purge gas	Flow rate (sccm)	2000	
	Time (sec)	30	
Reactant	Oxygen flow rate (sccm)	3500	
	Hydrogen flow rate (sccm)	1200	
	Time (sec)	10	
Purge	Flow rate (sccm)	2000	60
	Time (sec)	5	
Deposition process cycle number		140	

The thickness of the silicon oxide layer deposited under the conditions of Table 9 was measured through ellipsometer, and the growth rate and refractivity of the deposited silicon oxide layer are shown in Table 10.

TABLE 10

		Evaluation	Reactant	Substrate temperature (° C.)	Layer thickness [Å]	Growth rate [Å/cycle]	refractivity
5	10	ALD window (source feeding 10 sec)	Oxygen and hydrogen	550	140	1.00	1.48
				600	139	0.99	1.48
				650	137	0.98	1.48
				700	175	1.25	1.48
15	25	ALD window (source feeding 5 sec)	Oxygen and hydrogen	600	128	0.92	1.48
				650	127	0.91	1.48
				700	148	1.06	1.48
				650	24	0.17	1.48

According to Table 10, the refractivity of the deposited silicon oxide layer was maintained to about 1.48. It is considered because the thickness of the deposited silicon oxide layer is thin to a degree of less than about 200 Å.

The composition and ratio of the silicon oxide layer deposited under ALD window (about 550-750° C.) conditions were analyzed using an X-ray photoelectron spectroscopy (XPS) and a Secondary Ion Mass Spectrometry (SIMS), and the results are shown in Table 11.

TABLE 11

Evaluation	Source feeding time (sec)	Substrate temperature (° C.)	Composition of layer (at %)				
			C	N	Si	O	Si/O ratio
30	10	550	0	0	34.3	65.7	0.52
		600	0	0	34.1	65.9	0.52
		650	0	0	34.3	65.7	0.52
		700	0	0	34.4	65.6	0.52

Referring to Table 11, it was confirmed that no carbon and nitrogen were found in the silicon oxide layer formed in Example 5. This may mean that charge trap due to carbon or nitrogen atoms in the silicon oxide layer was also not produced. Therefore, leakage current through the silicon oxide layer could be prevented/reduced. In addition, the ratio of silicon/oxygen in the silicon oxide layer was maintained to similar values even though the temperature of the silicon substrate increased. In addition, the wet etching rate of the silicon oxide layer deposited in a range of about 550-700° C. was analyzed. Wet etching was performed twice for about 10 seconds each using hydrofluoric acid (H₂O: HF=200:1) as an etchant, and the thickness was measured by the number of etchings. The results are shown in Table 12.

TABLE 12

Evaluation	Substrate temperature (° C.)	Wet etching rate (Å/sec)	
		1 st Etching	2 nd Etching
55	550	4.2	3.0
		3.5	2.5
		2.7	1.5
		2.5	1.4

According to Table 12, it could be found that the etching rate is about 1.4 to about 3.0 Å/sec, and very excellent wet etching resistance was confirmed. In addition, according to the increase of the temperature of the substrate from about 550° C. to about 700° C., the etching rate of the deposited silicon oxide layer was reduced. Accordingly, it could be found that the etching resistance of the deposited silicon

17

9. A method of depositing a silicon-containing layer, the method comprising:

- feeding a substrate into a process chamber;
- heating the substrate to a temperature of about 550° C. to about 700° C.; and
- repeating a deposition process cycle until the silicon-containing layer is a set thickness,

wherein the deposition process cycle comprises

- feeding a silicon precursor into the process chamber after the heating of the substrate such that the silicon precursor is adsorbed onto the heated substrate, the silicon precursor represented by Formula 1
- purging the process chamber of the silicon precursor which is not adsorbed on the heated substrate;
- feeding a reaction gas into the purged process chamber to react with the silicon precursor adsorbed on the heated substrate; and
- purging the reaction gas which is unreacted with the silicon precursor,

<Formula 1>

10

20

18

wherein

the R¹ is hydrogen or an alkyl group of 1~6 carbon atoms, and

the R² and the R³ are each independently an alkyl group of 1~6 carbon atoms, and

wherein the substrate is maintained at about 550° C.-700° C. during the feeding of the silicon precursor into the process chamber, and

wherein the silicon precursor is thermally stable at 500°

C. or greater under atmospheric pressures, and

wherein the A¹ is a heterocyclic group represented by Formula 3

<Formula 3>

in Formula 3, the p and the q are each independently an integer of 0 to 2, and

the A² is an oxygen atom (O) or NR⁴, where the R⁴ is an alkyl group of 1~6 carbon atoms.
